(57) **CLAIM**

An ornamental design for a "fireplace assembly," as shown and described.

DESCRIPTION

FIG. 1 is a front perspective view of the fireplace assembly;
FIG. 2 is a front side view of the fireplace assembly;
FIG. 3 is a rear side view of the fireplace assembly;
FIG. 4 is a right side view of the fireplace assembly;
FIG. 5 is a left side view of the fireplace assembly;
FIG. 6 is a top side view of the fireplace assembly; and,
FIG. 7 is a bottom side view of the fireplace assembly.
The broken lines and the spaces therein represent environmental subject matter and form no part of the claim.
